UNITED STATES PATENT OFFICE

2,440,738

LIQUEFIED GAS EXTRACTOR

Howell C. Cooper, Sewickley, Pa.

Application August 18, 1945, Serial No. 611,278

3 Claims. (Cl. 62—1A)

1

This invention relates to extraction of liquefied gas from a closed container, and more particularly contemplates extraction of liquefied natural gas from a large container wherein the liquid has been stored, at a temperature in the order of a -250° F. and at atmospheric pressure or only slightly thereabove as has become a practice for standby purposes in the natural gas industry.

The invention contemplates storage in a tank or bottle or plurality thereof, in the order of 40 feet or more in height, buried or largely disposed in the ground so that a bottom drainage opening would be impractical.

Objects of the invention are to provide extraction of such liquid with the least heat loss thereinto and consequent gasification thereof, and with a minimum of power, by inexpensive means adapted to serve a large number of containers; all as will appear hereinafter.

Further objects and advantages will be apparent from the following description taken in connection with the accompanying drawing which is a more or less diagrammatic and conventionalized view illustrative of an embodiment of the invention.

With reference now to the drawing, 1 is the container for liquefied gas, which may be provided with suitable insulation and buried in the ground, and may be one of many there located. It has a single opening only, located at the top, through which it may be charged with liquefied gas by way of a pipe 2 having a suitable vent 3. 4 is a tank into which it is desired the liquid contents of the container 1 be transferred, the tank 4 being in practice at a higher elevation than the container 1, so that its liquid may be withdrawn as desired by gravity through the outlet pipe 4a.

According to this invention, the container 1 is provided with pump means of the air-lift type, comprising outer and inner tubes 5 and 6, respectively, the tubes extending downwardly into the container but terminating with open ends short of the bottom thereof, the inner tube 6 being perforated adjacent its lower ends, as indicated at 6a, and the outer tube 5 being closed at its upper end with the exception of the tube 6 which extends therethrough. As will be appreciated by one familiar with the art, the arrangement is such that when the gas is pumped into the upper end of the tube 6, it will produce bubbles of vapor at the lower end, which bubbles will rise in the annular space between the two tubes entraining the liquid, the column of mixed

2

gas and liquid rising and finding an exit from the container by way of the pipe 7.

According to this invention, the gas employed in the pump is the vapor of the liquid contents of the container 1 and the stream of this vapor is provided by a compressor 8 in a circuit to be described. This circuit includes a line 9 leading from the compressor 8 to the inlet end of the pump tube 6 with a connection 10 providing communication with the space within the container 1 above the liquid therein. The connection 10 is preferably valved as at 10a or otherwise somewhat restricted so that the pressure applied to the tube 6 will be sufficiently greater than that above the liquid so that the pump will operate as described.

The liquid outlet pipe 7 leads into a separator 11 from the bottom of which liquid gas flows to the tank 4 by way of the pipe 12, the vapor emerging from the top of the separator by way of the pipe line 13 leading to the compressor 8. The top of the tank 4 may be vented to the line 13 as indicated at 14. The line 9, after the compressor 8, may be vented as at 15, valved as indicated so that the system may be relieved of excess vapors; in practice, the connection 15 leading to the gas distributing system to be served by the regasified liquid, and a second compressor, not illustrated, being employed if necessary to overcome the pressure of such distributing system.

In order to minimize regasification within the system, a heat exchanger 16 is provided, arranged in the lines 9 and 13 as indicated, to cool the vapor discharged by the compressor and not vented at 15, by the refrigeration effect of the vapor leaving the separator 11 and received from the tank 4 by way of the connection 14.

Where the system is to serve a number of containers 1, suitable valved connections 17 and 18 are located in the lines 7 and 9, respectively, which latter are valved as at 19 and 20, so as to provide optional application of the system to selected containers to be emptied—all as will be evident to one familiar with the art.

I claim:

1. The method of extracting liquefied gas from a closed container comprising coincidentally entraining portions of the liquid contents of said container in an outflowing stream of vapor of said liquid, separating the liquid and vapor portions of said stream, and returning a sufficient portion of the separated vapor to said container to provide said stream and to displace the liquid entrained thereby.

5 tainer, the liquid and vapor contents of the combined stream, compressing said separated vapor contents to provide circulation of said stream, venting a portion of the compressed vapor, cooling the remaining portion of the compressed vapor by said separated vapor contents, and returning said remaining cooled stream portion to said container to provide said entrainment stream and to displace the liquid entrained thereby.
